UNITED STATES PATENT OFFICE.

FREDERICK A. PRESTON, OF HIGHLAND PARK, ILLINOIS, ASSIGNOR TO THE P. & M. CO.,
OF CHICAGO, ILLINOIS, A CORPORATION OF ILLINOIS.

TWO-WAY ANTICREEPER.

1,217,127.

Specification of Letters Patent. Patented Feb. 20, 1917.

Application filed February 19, 1916. Serial No. 79,311.

To all whom it may concern:

Be it known that I, FREDERICK A. PRESTON, citizen of the United States, residing at Highland Park, in the county of Lake 5 and State of Illinois, have invented a certain new and useful Improvement in Two-Way Anticreepers, of which the following is a full, clear, concise, and exact description.

10 My invention relates to improvements in two-way anti-creepers for railroad rails.

The object of the invention is to provide an effective device which shall be inexpensive to manufacture.

15 In the accompanying drawings, in which one embodiment of the invention is illustrated,

Figure 1 is an elevation of the anti-creep, the rail being shown in section.

20 Fig. 2 is a top plan view thereof with the rail partly in section.

Fig. 3 is a perspective view of the longitudinal member.

25 Fig. 4 is a perspective view of the transverse member.

The rail 1 is supported on the usual cross-ties 2. A longitudinal member 3 is provided which rests preferably on the top of one of the base flanges of the rail and has lateral 30 extensions 4 at opposite ends, provided with suitable openings to receive spikes 5, whereby said member is secured to two adjacent ties. A transverse member 6 is arranged beneath the rail base and has one end 7 bent 35 to form a jaw which embraces not only the side of the rail base, but the longitudinal member 3 as well. Means are provided for preventing relative longitudinal movement of the longitudinal member and the trans-

40 verse member. In the drawings I have illustrated rivets 8 for this purpose, although other means may be employed. The transverse member 6 has a downward extension 9 at its other end beneath the rail base, said

45 extension having a notch 10 adapted to receive the lower hooked shaped end of a clip 11. The upper end of said clip is provided with a flat surface 12 which bears against the upper side of the rail base forming

50 a jaw, the rail being gripped between said surface and the upper surface of the transverse member 6. The clip is put in position by first hooking the lower end into the notch and then driving the upper end 55 over the rail base, whereupon the rail an-

chor is maintained in firm frictional engagement with the rail base and tends to move therewith when the rail creeps in either direction. The creeping thrust produced by the rail is distributed over a plurality of ties through the medium of the longitudinal member 3. Said member may be extended to cover more than two ties, if desired.

60 This rail anchor is particularly economical and advantageous on a single track railroad where creeping takes place in two directions. Each one of these two-way anchors, when fastened to two ties, secures results which could be obtained only by the use of four of the common type of rail anchors. Under some conditions, for example on double track roads, the anti-creep may be secured to one tie only and correspondingly shortened. An advantage of the particular construction illustrated is that all 65 of the parts are made from flat bars or metal plate, whereby the expense of manufacture is a minimum. However, the invention is not limited to these materials nor to the particular configuration illustrated, as it may be embodied in various other forms.

70 What I claim as new and desire to secure by Letters Patent of the United States is:

75 1. An anti-creep comprising means in direct engagement with a rail base for gripping opposite sides thereof, and means arranged between part of said rail gripping means and the rail for distributing the creeping thrust over a plurality of ties.

80 2. An anti-creep comprising a transverse member beneath the rail base having a jaw at one end thereof in frictional engagement with said rail base and a longitudinal member arranged between part of said jaw and said rail base and extending to an adjacent tie.

85 3. An anti-creep comprising a transverse bar beneath the rail base, a longitudinal bar on top of the rail base, said transverse bar being bent over and secured to said longitudinal bar and means for maintaining said parts in position on the rail.

90 4. An anti-creep comprising a transverse element having a rail gripping jaw at one end and having a downward projection at the other end, a clip for holding said other end against the rail base in frictional engagement therewith, and a longitudinal member secured to a plurality of adjacent

100

110

ties and coöperating with said transverse element to transmit the creeping thrust to said ties.

5. An anti-creeper comprising a transverse bar beneath the rail base having one end bent around to form a jaw and having the other end bent downwardly and provided with a notch, and a metal clip coöperating with said notch and bearing against the top of the rail base to hold the anti-creeper in frictional engagement with the rail.

6. An anti-creeper comprising a transverse member beneath the rail base, a longitudinal member on top of the rail base, said transverse member extending upwardly at the side of the rail base and coöperating with said longitudinal member to transmit

the creeping thrust thereto, and means at the other side of said rail base coöperating therewith and with said transverse member to maintain the anti-creeper in frictional engagement with said rail base.

7. An anticreeper comprising a member arranged transversely beneath the rail base, a vertical member at one end thereof for holding said transverse member in frictional engagement with said rail base, and a longitudinal member clamped between the other end of said transverse member and said rail base for transmitting the creeping thrust to a cross tie.

In witness whereof, I hereunto subscribe my name this twelfth day of February A.D., 1916.

FREDERICK A. PRESTON.
